STOKER MECHANISM

Herman L. Kraeft, Cleveland, Ohio, assignor to
 The Murray Ohio Manufacturing Company,
 Cleveland, Ohio, a corporation of Ohio

Application January 4, 1933, Serial No. 650,094

3 Claims. (Cl. 110—115)

This invention is concerned with improvements in stokers of the overfeed type, and has for its general object the provision of a fuel spreader and adapter mechanism utilizable in connection with such stokers for conveniently and efficiently adapting the stoker mechanism to furnaces and boilers of different types and sizes while fulfilling the varying requirements due to variations in grate areas and fire door dimensions.

More specifically, my invention is directed to the provision of a mechanism which will serve to spread the fuel in an even manner over the fire bed when the fuel is presented to the fire door of the furnace by associated stoker mechanism and which will be efficient regardless of variations in burning characteristics of the fuel being fed to the fire bed.

Other objects of my invention will hereinafter become apparent from the following description, which refers to the accompanying drawings and the drawings illustrate a preferred embodiment thereof in association with a fuel feeding mechanism and hopper of the so-called "overfeed stoker type". The essential characteristics of the invention are summarized in the claims.

In the drawings, Fig. 1 is a longitudinal section of a mechanism embodying the features of my invention; Fig. 2 is a cross-section, looking toward the door frame of a furnace, equipped with my invention and corresponding to the lines 2—2 in Fig. 1; Fig. 3 is a cross-sectional view, taken through a fuel flipper means, comprising part of the mechanism and corresponding to the lines 3—3 in Fig. 1; Fig. 4 is an enlarged cross-sectional view of part of a bearing mechanism and taken along the lines 4—4 of Fig. 5; Fig. 5 is a horizontal section taken through part of the housing mechanism of the adapter, substantially along the lines 5—5 of Fig. 1; Fig. 6 is an enlarged cross-sectional detail of a fuel flipper member and associated fuel guiding means taken substantially along the lines 6—6 of Fig. 5; Fig. 7 is an enlarged fragmentary view of the fuel flipper mechanism; Fig. 8 is an enlarged cross-sectional detail of a bearing mechanism; Fig. 9 is a transverse section taken through the stoker gear drive substantially along the line 9—9 of Fig. 1 and Fig. 10 is a perspective of a fuel escape ledge.

My invention contemplates the use of a rotary element having peculiar characteristics of design, which will function to act upon coal particles as the same escape from a feed tube positioned in the fire door of a furnace and the purpose is to provide a mechanism which will be efficient in its functioning in spreading fuel particles by

flipping the same over the firebed, regardless of the type of mechanism which is utilized to present the fuel to the fire door, and I propose to use an associated housing mechanism in the form of a fire door stoker adapter, which will protect the rotary element and its bearings from attendant heat reflected from the fire pit of the furnace. I arrange this rotary element and its adapter housing in such manner that the rotary element can always be positioned in definite relation to the fire pits of furnaces, regardless of variations in furnace designs, and particularly the variations of the width of the fire door frame. This rotary element can be driven at any desired speed which will meet the fuel spread requirements of grate areas of furnaces of different designs. The adapter housing and rotary element are of such interrelation that the adapter and the rotary element may be associated with any form of fuel-feeding means of a stoker which will deliver the fuel to the fire door.

Referring to the drawings, and particularly to Fig. 1, my invention is illustrated as being associated with a fuel-feeding mechanism of a stoker, comprising a screw conveyor 10, disposed within a fuel guide tube 12, which extends into the fire door opening 14 of a furnace structure 16. The fuel feed tube 12 is substantially horizontally disposed in the present illustration, although it may be disposed at any convenient angle. Connected to the tube and communicating with the interior thereof is a fuel chute 18, having communication with the opening of a hopper 20. The screw conveyor 10 is suitably rotatably mounted on bearings 22 and 24, comprising part of the frame structure 28, of the stoker mechanism and is rotated by a worm gear 26, the worm gear being driven by a worm 28 carried by a transversely extending shaft 27. The shaft 27 is rotatably mounted in suitable bearings comprising part of the stoker frame. The worm shaft 27 carries a gear 29 which is driven by a gear 30, the latter gear being mounted upon a small stud shaft 30 and the gear 29 being attached to a sprocket wheel 31, which is driven by sprocket wheel 32 mounted upon shaft 33 of a motor 34 adjustably attached at 36 to the underside of the stoker frame. A driving chain 40 serves to connect the two sprocket wheels 31 and 32. The stoker frame may be supported in any suitable manner, such as an overhead suspension, attached to the ceiling of the furnace room or upon a frame resting upon the floor in front of the furnace.

The fuel flipper mechanism, the manner of mounting the same within the adapter and hous-

ing mechanism, and the relation of the adapter mechanism to the fuel feeding mechanism of the hopper will now be described.

A rotary fuel flipping or impelling element 50 is shown as being mounted upon a shaft 51, the element being disposed to rotate on self-aligning bearing mechanism generally indicated at 52 and 53, (see Figs. 1, 2, 3, and 5) and this rotary element, with attendant bearing mechanism, is supported within a housing in such manner that the shaft 51 of the rotary element extends across the door opening, with the rotary element disposed adjacent the fire pit edge 55, (see Fig. 1) of the furnace and in the lower part of the door opening. The housing construction is such that the upper part thereof forms a passageway for the passage of fuel from the fuel feeding means to an adjustable ledge member 60, the function of which will be hereinafter described. The housing comprises a box-like structure, of comparatively open construction as viewed from the front of the furnace, but arranged to enclose the bearing mechanism supporting the fuel flipper 50, when viewed from the fire side thereof. Hence, this construction may comprise a bottom panel 62, secured to the side panels 63 and 64, in any convenient manner, such as welding, the side panels 63 and 64 being similarly attached to a top panel member 65. The inner or fire side of the housing structure comprises a metallic panel 68, suitably secured to the top, bottom and side panels just described, and this fire side panel is provided with a rectangular opening, the width of which is substantially equal to the length of the rotatable flipper member 50. An extension on the fuel-feeding tube 12 is provided, comprising a metallic member 70, which, in the present instance, is round at the outer end thereof to telescopically fit the inner end of the fuel-feeding tube 12, at a point which is exterior of the fire door frame of the furnace, as shown in Fig. 1, while the inner end 70a of the tube is flared to a rectangular shape, (see Figs. 1 and 2) whereby the inner rectangular opening thereof will have a width substantially equal to the length of the fuel flipper 50 and the height substantially corresponding to the diameter of the fuel feed tube 12. It will be apparent, from Fig. 2, that this width is substantially less than the width of the housing structure to afford a support and a housing for the bearing mechanisms 52 and 53 and to afford room for a sprocket wheel 78, mounted upon the flipper shaft 51. I provide two inner vertically disposed panel walls 80 and 81, which extend from the top panel member 65 to the bottom panel 62, and which are spaced apart a distance substantially equal to the length of the flipper 50, and the inner fuel discharge width of the tube 70.

To completely close the space between the housing for the fuel feeding mechanism and the walls of the fire door of the furnace when the apparatus is in operative position, I provide a shell structure in sliding engagement with the bottom panel 62, top panel 65, and side panels 63 and 64, comprising top and bottom members, 88 and 89, respectively, and side panels 90 and 91, which are flanged to engage a closure panel 92 (see Fig. 2) which may be of sufficient dimensions to close the largest furnace door opening by contacting with the outer edge thereof. The inner housing panels 62 and 63, 64 and 65, and the outer panels 89, 91, 90 and 88 are in respective sliding or telescopic engagement. It will thus be apparent that the inner fire front panel 68 of the housing is adjustable toward and away from the panel 92 to meet various depths

of fire door frames while at all times permitting of the disposition of the flipper 50 relative to the fire pit edge 55 in the relation shown. Any suitable means may be used to secure the housing panels in adjacent position, such as bolts 200 secured to the panel members 68 and extending through horizontally extending slots 90a and 91a formed in the panel members 90-91 and exteriorly disposed wing nuts 201 in threaded engagement with the bolts (see Fig. 5).

The rotary flipper 50 is driven from the worm shaft 27 by reason of the sprocket wheel 78 being driven by a chain 95, the chain 95 extending to and over a sprocket wheel 96 mounted on the worm shaft 27 at the forward end of the stoker mechanism.

The purpose and shape of the contour of the flipper will now be described. In the present design the diameter of the flipper 50 is about three and one-half inches and the length about six inches. Upon the circumferential surface are formed four equidistantly spaced impeller ridges 100, comprising radial surfaces 101 at the end portions of the flipper and centrally disposed forwardly converging surfaces 102, which function as a sort of a wedge to impart to fuel particles falling over the forward edge of the ledge 60 a fire bed spreading movement. A semi-cylindrical housing 108 partially encloses the flipper 50. The lefthand side of this housing (Fig. 6), is provided with a flange 108a which slopes toward the firebed and is engaged by a similar flange 108b which is attached to the housing panel 62. It will be apparent that by adjusting the edge 60a, of the ledge 60, in a tangential direction relative to the circumferential path of movement of the flipper 50, a considerable range of regulation of the flipping action of the flipper 50 upon the fuel particles, as the latter fall over the edge 60a, is obtainable. It will also be apparent that the housing arrangement of the flipper 50 is such that fuel particles cannot fall to a place of rest adjacent the firebed. Fire hazards thus are eliminated, particularly when the stoker mechanism is not in operation, and there is a fire in the furnace.

The bearing mechanism for the flipper shaft 51 is constructed in such manner as to be practical under comparatively high temperatures, due to heat radiance from the fire pit and conduction of the metallic parts comprising the flipper and the housing. Accordingly, I arrange this bearing mechanism in such manner as to be also operative should the various metal panels comprising the housing warp. Hence, the bearing mechanism may comprise a block of hard graphite 113 encased in spherically formed retainers 111, which bear in a bearing bracket 112, secured to the housing panel 62, and having upper flanged portions 112a and 112b, shaped to be complementary to the spherical surface of the graphite retainer 111, to loosely engage the same whereby the bearings 113 may float in the brackets. The retainers 111 and the graphitic blocks carried thereby are slotted in the upper parts thereof to receive sticks of lubricating graphite 115, and I provide slidable weights 116 to bear upon the upper projecting ends of the lubricating graphite blocks 115 to thus maintain the lubricating graphite in contact with the ends of the shaft 51.

As herein before stated, the ledge 60 may be adjusted relative to the circumferential path of the flipper 50. I find that the desired position of the ledge is dependent upon the speed of rotation of the flipper 50, and the degree of fineness or coarseness of the fuel which is being fed

by the apparatus to the furnace. To facilitate such adjustment, the ledge 60 is provided with two downwardly extending flanges 60b, which are slidably mounted on the inner vertical walls 80—81 of the housing structure. A clamping bar 130, having one end threaded to receive a clamping nut 131, is disposed within a tube 132 of a length to about the inner faces of the flanges 60b and passes through elongated openings or slots 60c in the flanges. It will be thus apparent that the ledge 60 can be slidably adjusted relative to the rotary flipper 50 in a convenient manner, without necessitating any disorganization of the elements of the housing structure.

From the foregoing it will be apparent that I have provided a fuel spreader mechanism, arranged in a very compact manner for adaptation to stoker mechanisms of various mechanical types and which will function to deliver coal to a fire door whereupon my invention will be quite efficient in the application of the fuel particles to the fire bed. This mechanism is arranged in such manner that it is readily adaptable to furnaces of varying designs, that is, furnaces with fire pits or fire boxes of different shapes, such as square, round and rectangular or elongated. Structural variations of the fire door frame are met by the ready adaptability of the housing structure and coal passageways of the device, whereby the fuel is caused to enter at the upper part of the fire door and thereafter caused to be flipped to the fire bed without undue agitation thereof. Variations in fuel characteristics are met by the adjustability between the relationship of the fuel spreader or flipper mechanism and the fuel passageway in that the adjustable ledge I provide is such as to function in controlling the falling movement of the fuel particles relative to the circumferential path of movement of the fuel spreading means. The construction is such that any external obstruction about the furnace installation need not be a serious detriment to a quick installation of a stoker mechanism used in association with my invention, in that the ultimate position of the stoker mechanism proper relative to the fuel spreading means is adjustable throughout a considerable length, which adjustments do not in any manner interfere with the efficient positioning of the fuel spreader means relative to the firepit of the furnace. All of this I accomplish by incorporating my mechanism in a housing which may be of such construction as to be quite economically manufactured; the construction may be light and formed of heat resisting sheet metal, and the arrangement is such that when the stoker mechanism is shifted to fuel feeding position relative to the furnace fire door the fire door opening is completely closed while the fuel spreader mechanism is positioned within the fire door frame immediately adjacent the fire bed. Radiant heat influences of the fire bed upon the mechanism are offset through external ventilation by reason of the open construction of the housing as viewed from the front of the furnace.

Protracted experimenting has proved that the device is highly efficient in spreading the fuel over the firebed when proper adjustments are made to meet the particular firebed environment. The loss of the finer fuel particles up the stack before complete combustion is avoided and the usual fire hazards incident to the use of overfeed stokers which are automatically operated by thermostatic control over considerable periods of time without observation are avoided.

I claim:

1. In a stoker of the overfeed type, the combination of a fuel delivery tube adapted to extend into a fire door opening, a rotary element adapted to be disposed within the fire door opening adjacent the fire pit edge thereof, means for forcing fuel through said tube and means for driving said rotary member, a housing construction supporting the rotary member in cooperative relation to the tube, and a second housing surrounding the first-named housing and comprising a closure for space between the walls of the first-named housing and the fire door wall when the housings are in operative position relative to the fire door opening, said first-named housing being relatively adjustable longitudinally of the tube whereby the position of the rotary element may be adjusted relative to said fire pit edge.

2. The combination with a furnace having a fire door opening of an overfeed stoker, comprising a substantially horizontal fuel conveying tube with a transverse cross-sectional area substantially less than the fire door opening of the furnace, a housing disposed within the door opening connected in telescopic and adjusted relation with said tube, a rotary fuel spreader carried by said housing within said door opening, a second housing for closing the space between the walls of the first housing and the walls of the fire door opening, said second housing being telescopically arranged relative to the first housing, means for feeding fuel through said tube toward the first housing and to the rotary spreader, to spread the fuel in the furnace and means for driving the rotary spreader.

3. The combination with a furnace having a fire door frame, of an overfeed stoker comprising a substantially horizontal fuel conveying tube, a housing mounted within the fire door frame, a rotary fuel spreader carried by said housing, a second housing comprising a closure for the space between said housing and the walls of the fire door frame, said first housing having a telescopic connection with said second housing, whereby the fuel spreader may be adjusted toward and away from the fire pit edge, an extension for said tube telescopically arranged relative to said tube and said first-named housing whereby the length of said tube may be adjusted relative to the fuel spreader and means to progress fuel through said tube and to operate said rotary spreader.
